UNITED STATES PATENT OFFICE

2,436,763

WRITING INSTRUMENT

Russell T. Wing, Excelsior, Minn.

Application March 23, 1946, Serial No. 656,627

13 Claims. (Cl. 120—42)

1

This invention relates generally to quick-detachable coupling devices and has to do more particularly with devices of that character which are especially well adapted for use on fountain pens and the like.

The principal object of my invention is to provide a coupling device which is positive and which is devoid of any likelihood of becoming uncoupled except in response to a manipulation which is intended to bring about that result; yet which is very simple and easy to operate.

Another object is to provide a positive coupling device having the above-indicated characteristics and which can be used on fountain pens and the like without impairing the appearance thereof.

Still another object is to provide a positive coupling device for fountain pens and the like which is dependable and durable and yet capable of being manufactured economically.

A further object is to provide, in combination with my positive coupling device, spring biasing means operative to neutralize any looseness which might otherwise exist in the coupling device and which is further effective, as applied to a fountain pen, to aid in separating the cap from the pen when the coupling is released.

An additional object is to provide in a fountain pen, in combination with my positive coupling device, an axially spring-pressed sealing cap which functions to enclose the writing nib and thus prevent or diminish drying out of the nib, while at the same time operating to neutralize all looseness in the coupling device and to aid in separating the cap from the pen when the coupling is released.

My new coupling device, as applied to a fountain pen, involves an annular shoulder encircling the pen barrel and adapted to latching engage one or more (preferably several) spring fingers carried by the cap and operative to snap into engagement with said shoulder when the cap is put on—the cap being thus positively secured to the pen. Formed adjacent said shoulder and corresponding numerically to the spring fingers are one or more (generally several) cam surfaces which are effective, when the cap is rotated a few degrees, to lift the spring fingers out of the path of said shoulder so that the cap can thereupon be withdrawn from the barrel. In order to ensure that the spring fingers will invariably be engaged by the cam surfaces and thus lifted out of the path of the shoulder, in response to an appropriate rotation of the pen cap, it is desirable to spring-bias the cap in the direction in which it is withdrawn from the pen; and in so doing I

2

not only ensure that a disconnecting manipulation will always be effective, but I also facilitate the cap removal operation by making it unnecessary for the pen user to apply tension to the cap when he is rotating it to release the coupling. At the same time, the aforementioned spring bias is effective to continuously retain the spring fingers in contact with the shoulder—thus eliminating any unbecoming axial play which might otherwise result from even a small amount of clearance between the ends of the spring fingers and the shoulder. The spring bias is preferably applied through the medium of the aforementioned sealing cap.

15 For purposes of illustration only, I have shown in the accompanying drawing one of the preferred embodiments of my invention, but it is to be understood that many modifications and alternative forms are possible within the scope of my inventive concept.

Referring to the drawing:

Figure 1 is a view, partly in side elevation and partly in longitudinal section, of a fountain pen and receptacle with a detachable coupling in accordance with this invention;

Fig. 2 is an enlarged fragmentary longitudinal sectional view;

Fig. 3 is a detailed view taken along line 3—3 of Fig. 2;

30 Fig. 4 is a longitudinal sectional view taken along line 4—4 of Fig. 2 and showing the construction of the spring sleeve—the pen being omitted from this view;

Fig. 5 is a transverse section taken along line 35 5—5 of Fig. 4;

Fig. 6 is a transverse section at line 6—6 of Fig. 2;

Fig. 7 is a transverse section identical with Fig. 6 except that it shows the spring fingers lifted 40 out of the groove;

Fig. 8 is a view illustrating a modification of the invention;

Fig. 9 is a transverse section along line 9—9 of Fig. 8;

45 Fig. 10 is a transverse section similar to Fig. 9 but showing the barrel of the pen rotated thirty degrees with reference to the spring fingers;

Fig. 11 is a transverse section similar to Figs. 9 and 10, showing the spring fingers in the course 50 of being lifted out of the groove; and

Fig. 12 is a transverse section similar to Fig. 11, showing the completion of the unlatching operation which is shown partially completed in Fig. 11.

55 The device of Figs. 1 to 7, inclusive, is shown in

full in Fig. 1 and comprises an elongate cup-like receptacle or carrier 1 and a fountain pen 2 shown inserted in the receptacle with the point down. Receptacle 1 is intended to be carried in the pocket of a vest or coat, as fountain pens are usually carried; and it is provided with a pocket clip 3, which forms the subject matter of my co-pending application, Serial No. 656,628, filed March 23, 1946.

The rear end of the pen projects out of the receptacle, as shown in Fig. 1, and it is removably secured in the receptacle by means of a novel latching means which forms the subject matter of the instant application and will presently be described.

Mounted within the lower end of receptacle 1 is an inner cap 4 which is designed to receive the front end of the pen, as shown in Fig. 1, and to form a seal against excessive ink evaporation. A coil spring 5 continuously urges cap 4 and pen 2 upwardly.

When pen 2 is inserted in receptacle 1 and pushed down against the pressure of spring 5, the latching means about to be described automatically locks the pen in the receptacle so that it cannot be shaken loose. But the pen is releasable from the latching means by manually rotating it a few degrees about its longitudinal axis.

There is formed in the barrel of the pen an external circumferential groove 6 which is adapted to latching engage a pair of oppositely disposed spring fingers 7 and 8, the free ends of which are bent inwardly to engage the groove. Fingers 7 and 8 are integral parts of a spring sheet metal sleeve, the form of which is best shown in Figs. 2 and 4. Said sleeve is pressed into the bore of receptacle 1 and is anchored thereon by means of an outwardly projecting lug 9a which extends through a slot-like opening in the wall of receptacle 1. The spring fingers are, of course, biased inwardly so that they will snap into groove 6; and any desired number of such fingers may be employed. I find that two are generally sufficient and that one will answer the purpose. In order to release the pen for withdrawal from the receptacle it is necessary to lift the ends of the spring fingers out of groove 6; and to effect that end I provide cam means which act on the spring fingers in response to manual rotation of the pen. With the specific latching device of Figs. 1-7, the pen can be released only by rotation thereof in a given direction; but with the alternative arrangement of Figs. 8-12, the pen is releasable in response to rotation in either direction.

Groove 6 (see Fig. 3) is defined on its rear or upper side by a continuous shoulder 10, and on its front or bottom side by a shoulder of saw-tooth form or what may appropriately be referred to as a series of shoulders 11a to 11f, inclusive, each extending at a small angle to a plane which is normal to the longitudinal axis of the pen. Extending from the bottom of groove 6 to the outer surface of the pen barrel, at each step of the serrated shoulders, are sloping surfaces 12a to 12f. These are shown to best advantage in Figs. 3, 6 and 7.

Since spring 5 continuously pushes upwardly on the pen, it will be apparent that the serrated front or lower shoulder of groove 6 always bears against the ends of the spring fingers when these are in the groove; and it will be evident that if pen 2 is rotated clockwise, as viewed in Fig. 6, the two spring fingers will be engaged by two of the cam surfaces and will be lifted out of the groove

5 to a position where they no longer lie in the path of the saw-tooth shoulder—whereupon the pen will be lifted by spring 5 to such an extent that groove 6 is out of registration with the ends of the spring fingers. The pen can then be lifted out of the receptacle, or it can be relatched by pushing down thereon.

The shoulder 10 functions only as a stop for limiting the downward movement of the pen. 10 It can be eliminated without detracting from the invention.

15 While it is preferable that the serrated shoulder completely encircle the barrel of the pen, this obviously is not essential; and it is not essential that there be more than one position of rotation at which cam means are provided for lifting the spring fingers.

20 In the alternative embodiment of the invention depicted in Figs. 8 to 12, the pen-holding receptacle or carrier is identified by reference numeral 15. The pen itself is identified by reference numeral 16. Mounted within the receptacle and secured thereto is a spring sleeve 17 having a pair of oppositely disposed spring fingers 18 and 19. A circumferential groove 20 is formed in the 25 barrel of the pen for latchingly engaging the in-turned ends of said spring fingers. The rear or top side of groove 20 is defined by a continuous circumferential shoulder 21, while the front or bottom side of the groove is defined by two series of arcuate shoulders arranged alternately. The members of one of said series of shoulders all lie in the transverse plane identified by reference numeral 22, in Fig. 8; and the members of this 30 series are identified by reference numerals 22a to 22f, inclusive. The members of the other series all lie in the transverse plane identified by reference numeral 23, in Fig. 8; and the members of this series are identified by reference numerals 23a to 23f, inclusive. It will be noted that transverse planes 22 and 23 are spaced apart lengthwise of the pen.

35 Shoulders 22a to 22f are formed by turning the annular groove 20, whereas shoulders 23a to 23f are formed by milling the barrel tangentially at angularly spaced points to a depth equal to the depth of the groove. This results in a series of 40 tangential bottom surfaces 24a to 24f, inclusive, which operate as cam surfaces to lift the ends of spring fingers 18 and 19 when the pen is rotated in either direction. As in the previously 45 described structure of Fig. 1, a spring is provided which continuously urges pen 16 upwardly. Thus, the ends of the spring fingers are always in pressure contact with shoulders of one or the other of the two above-described series. In Figs. 8 and 50 9 the spring fingers are shown in alinement with shoulders 22a and 22d, respectively, whereas in Fig. 10 they are shown in alinement with shoulders 23a and 23d. When oriented as shown in Fig. 10, the ends of the spring fingers rest upon or overlie cam surfaces 24a and 24d, and if the pen is then rotated in either direction the spring fingers will be lifted by said cam surfaces out 55 of the groove to positions wherein they are clear of the front shoulders, as shown in Fig. 12. This operation is illustrated in Fig. 11. The pen is thereupon moved upwardly, as before, to a position wherein the spring fingers are out of registration with the groove. Regardless of the rotational orientation of the pen with respect to the spring fingers, the latter will latching engage a pair of front shoulders of one series or the other and can be disengaged therefrom only by 60 rotating the pen until the ends of the spring fingers 65 70 75 are lifted out of the groove.

gers are lifted by one or another pair of cam surfaces. If the pen is provided with six front shoulders per series, as shown, the maximum rotation required to complete an unlatching operation is 90 degrees. The minimum necessary rotation is 30 degrees, which will obtain if the pen happens to be latched with the spring fingers in alinement with a pair of shoulders in the 23 series.

It will be apparent that a single spring finger would answer the purpose and that more than two may be employed, if desired; and it also will be apparent that the invention could be carried out with one spring finger and only one cam surface and one shoulder of series 23. But it generally is desirable to provide several cam surfaces and several shoulders of the 23 series so that the unlatching operation can always be effected with a relatively small angle of rotation.

I claim:

1. In a writing instrument, a first member, a second member adapted to be detachably coupled to said first member, said members being relatively rotatable about a common axis and separable, when uncoupled, by relative movement lengthwise of said axis, said first member having a shoulder trending circumferentially of said axis, said second member having a spring-pressed element adapted to cooperate with said shoulder to latch said members together axiswise when said members are brought together, said first member having a cam surface adjacent said shoulder which is operative, in response to relative rotation of said members about said axis, to lift said element out of the path of said shoulder whereby to unlatch said members and thus enable separation thereof.

2. In a writing instrument, a first member, a second member adapted to be detachably coupled to said first member, said members being relatively rotatable about a common axis and separable, when uncoupled, by relative movement lengthwise of said axis, said first member having a continuous series of arcuate shoulders, said series trending circumferentially of said axis, each of said arcuate shoulders extending at a small angle to a plane normal to said axis, each of said shoulders being defined bottomwise by a cam surface, said second member having a spring-pressed element adapted to cooperate with said shoulders to latch said members together axiswise when said members are brought together, said element being adapted to be acted upon by any of said cam surfaces and to be lifted thereby out of the path of said shoulders in response to relative rotation of said members about said axis.

3. In a writing instrument, a first member, a second member adapted to be detachably coupled to said first member, said members being relatively rotatable about a common axis and separable, when uncoupled, by relative movement lengthwise of said axis, one of said members having an arcuate groove, trending circumferentially of said axis, the other of said members having a spring-pressed element adapted to snap into said groove when said members are brought together along said axis, said element being operative, when engaged with said groove, to positively couple said members together, and cam means operative in response to relative rotation of said members about said axis, to lift said element out of said groove, thereby uncoupling said members.

4. In a writing instrument, a first member, a second member adapted to be detachably coupled to said first member, said members being relatively rotatable about a common axis and sep-

arable, when uncoupled, by relative movement lengthwise of said axis, the first of said members having an area which is reduced diametrically to form two lengthwise contiguous shoulders, each trending circumferentially of said axis, said shoulders being mutually displaced lengthwise of said axis, the second of said members having a spring-pressed element which is operative, when said members are brought together along said axis, to assume a position in latching relation to said shoulders by virtue of which said members are positively coupled together, said first member having a cam surface which is operative in response to relative rotation of said members to lift said element to a position wherein it is non-engageable by either of said shoulders during a subsequent separating movement of said members lengthwise of said axis.

5. In a writing instrument, a cylindrical barrel, a tubular cap adapted to fit telescopically over one end of said barrel, a spring finger carried by said cap, said barrel having an annular peripheral groove operative to receive one end of said spring finger for locking said cap on said barrel, and cam means immediately adjacent said groove, said cam means being operative, in response to rotation of said cap relatively to said barrel, to force said spring finger out of said groove whereby to enable withdrawal of said cap from the barrel.

6. In a writing instrument, a cylindrical barrel, a tubular cap adapted to fit telescopically over one end of said barrel, a spring finger carried by said cap, said barrel having an annular peripheral groove operative to receive one end of said spring finger for automatically locking said cap on said barrel when the cap is applied thereto, and a cam surface provided at one side of said groove and operative, in response to rotation of said cap relatively to said barrel, to disengage said spring finger from said groove whereby to enable withdrawal of said cap from the barrel.

7. In a writing instrument, a cylindrical barrel, a tubular cap adapted to fit telescopically over one end of said barrel, a plurality of spring fingers carried by said cap interiorly thereof and disposed in spaced relation circumferentially of said barrel, said barrel having an annular groove adapted to be engaged by the free ends of said fingers for locking the cap on the barrel, said barrel having a series of circumferentially spaced cam surfaces immediately adjacent the front side of said groove, said cam surfaces each being operative to lift one of said spring fingers, individually, out of said groove in response to a predetermined rotation of said cap relatively to said barrel, and spring means continuously urging said cap toward removal from said barrel.

8. In a writing instrument, a cylindrical barrel having a longitudinal axis, a tubular cap adapted to fit telescopically over one end of said barrel, a plurality of spring fingers carried by said cap interiorly thereof and disposed in spaced relation circumferentially of said barrel, said barrel having continuous circumferential exterior shoulder means adapted to latchingly engage the free ends of said fingers for releasably locking the cap on the barrel, said shoulder means comprising a first series of arcuate shoulders spaced apart circumferentially of the barrel, and a second series of arcuate shoulders likewise spaced apart circumferentially of the barrel and alternating circumferentially with the shoulders of the first series, the shoulders of the first series all being located in a first plane which is transverse to the longitudinal axis of the barrel, the shoulders of the

second series all being located in a second plane which is transverse to the longitudinal axis of the barrel, said first plane being spaced from said second plane lengthwise of said axis and located nearer the front end of the barrel than is the second plane, each shoulder of the first series being bordered bottomwise by a cam surface which is operative to engage the free end of one of said fingers and to lift the same out of the path of said shoulder means in response to a predetermined rotation of said cap relatively to said barrel, and spring means continuously urging said cap toward removal from said barrel, said spring means being effective to bring the free ends of said fingers into operative relations to said cam surface whenever the cap is rotated as before mentioned.

9. In a writing instrument, a cylindrical barrel having a longitudinal axis, a tubular cap adapted to fit telescopically over one end of said barrel, a plurality of spring fingers carried by said cap interiorly thereof and disposed in spaced relation circumferentially of said barrel, said fingers extending lengthwise of the barrel, said barrel having continuous circumferential exterior shoulder means completely encircling the barrel and adapted to latchingly engage the free ends of said fingers for locking the cap on the barrel, said shoulder means comprising a first series of arcuate shoulders spaced apart circumferentially of the barrel, and a second series of arcuate shoulders likewise spaced apart circumferentially of the barrel and alternating circumferentially with the shoulders of the first series, the shoulders of the first series all being located in a first plane which is transverse to the longitudinal axis of the barrel, the shoulders of the second series all being located in a second plane which is transverse to the longitudinal axis of the barrel, said first plane being spaced from said second plane lengthwise of said axis and located nearer the front end of the barrel than is the second plane, each shoulder of the first series being bordered bottomwise by a cam surface which extends from the periphery of the barrel to a point radially closer to the horizontal axis of the barrel and which is operative to engage the free end of one of said fingers and lift the same out of the path of said shoulder means in response to a predetermined rotation of said cap relatively to said barrel, and spring means continuously urging said cap toward removal from said barrel, said spring means being effective to bring the free ends of said fingers into engageable relation to said cam surfaces whenever the cap is rotated as before mentioned.

10. A writing instrument comprising an elongate barrel having an external encircling shoulder facing rearwardly of the instrument, a tubular outer cap fitting telescopically over the front end of said barrel and encircling said shoulder, a plurality of spring fingers carried by and disposed interiorly of said outer cap and spaced circumferentially around said barrel, each of said spring fingers latchingly engaging said shoulder when said outer cap is in place and adapted to snap into latching engagement therewith when

the outer cap is applied, cam means adjacent said shoulder and operative in response to rotation of said outer cap relatively to the barrel to lift said spring fingers out of the path of said shoulder, an inner cap mounted within said outer cap and adapted to receive the front end of said barrel telescopically, and a spring urging said inner cap rearwardly whereby to apply a biasing force tending continuously to withdraw said outer cap from the barrel and to maintain said spring fingers in firm contact with said shoulder.

11. A writing instrument comprising an elongate barrel having means thereon providing in effect an external encircling shoulder facing rearwardly of the instrument, a tubular enclosing cap fitting telescopically over the front end of said barrel and encircling said shoulder, a plurality of spring fingers carried by and disposed interiorly of said cap and spaced circumferentially around said barrel, each of said spring fingers latchingly engaging said shoulder when said cap is in place and adapted to snap into latching engagement therewith when the cap is applied, cam means associated with said shoulder and operative in response to rotation of said cap relative to the barrel to lift said spring fingers out of the path of said shoulder, and spring means within said cap operatively engaging the barrel when inserted therein, whereby to apply a biasing force tending continuously to withdraw the cap from the barrel and to maintain said spring fingers in firm contact with said shoulder.

12. In a fountain pen, a barrel having a pen point secured in one end thereof, a cap detachably fitted over one end of the barrel to conceal and protect said pen point when the pen is not in use, interlocking elements on said cap and barrel mutually engageable to lock the cap to the barrel, spring means to automatically urge said elements into interlocking relationship when said cap is axially fitted onto said barrel and a cam element on one of said cap and barrel operative to disengage said interlocking elements when said cap is relatively rotated on said barrel.

13. In a fountain pen, a barrel member having a pen point secured in one end thereof, a cap member detachably fitted over one end of the barrel to conceal and protect said pen point when the pen is not in use, a spring latch on one of said members, a latching shoulder on the other of said members positioned to be engaged by said spring latch when said cap member is axially fitted onto said barrel member, and a releasing cam on said other member positioned to engage said spring latch and move it out of engagement with said latching shoulder upon relative predetermined rotation of said members.
